UNITED STATES PATENT OFFICE

JOHN PRESTON MINTON, OF WHITE PLAINS, AND ABRAHAM S. RINGEL, OF BROOKLYN, NEW YORK, ASSIGNORS TO RADIO CORPORATION OF AMERICA, A CORPORATION OF DELAWARE

ELECTROACOUSTIC DEVICE

Application filed August 15, 1924. Serial No. 732,153.

Our invention relates to acoustic devices and particularly to electro-acoustic devices of the so-called loud speaker type. Our invention further relates to sound reproduction and amplification methods.

One of the principal objects of our invention is the provision of an electro-acoustic device possessing the following characteristics and advantages:

10 (1) Faithful reproduction and substantially uniform amplification of the sounds to be reproduced and amplified over a wide frequency range.

15 (2) Substantial elimination of the effects of interfering frequencies.

(3) Faithful reproduction and substantially maximum uniform amplification over a wide range of frequencies with the employment of a comparatively small amount of

20 power.

(4) Tonal quality control.

(5) Low manufacturing costs.

25 (6) Constructional features imparting rigidity to the device resulting in the substantial elimination of undesirable vibrations.

Other objects and advantages of our invention will be apparent from the following description taken in connection with the accompanying drawings, in which:

30 Fig. 1 is a perspective view of a cabinet and a preferred embodiment of our loud speaker mounted therein.

Fig. 2 is a combined perspective view and 35 schematic diagram of connections of a preferred embodiment of our invention.

Fig. 3 is a front elevation partly in section.

Fig. 4 is a side elevation of the horns.

Fig. 5 is a top plan view of the horns.

40 Fig. 6 is a top plan view partly in section of the horns with certain parts broken away to more clearly disclose their structural relationship.

Fig. 7 is a plan view of a diaphragm actuating device.

A preferred embodiment of our loud speaker comprises two electro-acoustic units A and B of different sizes and possessing different electrical and acoustical characteristics. The unit A is substantially resonant

to the lower range of audible frequencies while the unit B is substantially resonant to the upper range of audible frequencies resulting in the substantially uniform reproduction and amplification of sound over a much wider range of frequencies than is attainable with a single unit.

The unit A which is the larger of the two, comprises an exponential horn 1 and an electro-magnetic sound reproducer 2.

The horn 1, which is the longer of the two and which opens up at a slow rate, comprises an intermediate vertical tapering portion 3 of quadrilateral cross section, terminating at its upper end in an open horizontal flaring portion 4 communicating with openings 5 in cabinet 6 and at its lower end in a securing portion 7 of cylindrical cross section as shown.

The horn 1 may be appropriately secured to certain of the inner surfaces of the cabinet 6 by means of substantially L-shaped brackets 8.

The unit B, which is the smaller of the two, comprises a straight exponential horn 10 and an electro-magnetic sound reproducer 11.

The horn 10, which is the shorter of the two and opens up at a more rapid rate than horn 1, comprises a straight intermediate horizontal tapering portion 12 of quadrilateral cross section terminating at one end in an open horizontal flaring portion 13 and at the other end in a securing portion 14 of cylindrical cross section as shown.

The tapering portion 12 is inserted thru an opening 15 in one of the sides of the horizontal flaring portion 4 of horn 1, the opening of the horizontal flaring portion 13 coinciding with a section of the opening in the horizontal flaring portion 4 of horn 1, as shown, so as not to interfere with the sound waves emanating from the horn 1.

The horn 10 may be secured to horn 1 by welding, soldering or brazing them together at their edges of contact 15, 16 and 17 as shown, thereby effecting a strong and rigid structural arrangement; thus preventing excessive vibration, which is likely to introduce extraneous rattling noises.

The horns may be constructed from suit-

able metal stampings, which may be soldered, brazed or welded together at their edges. The metal employed should be of such a character and thickness as not to vibrate.

5 As the two electro-magnetic sound reproducers 2 and 11 are similar except as to size, the magnetic diaphragm of 2 being of greater diameter than that of 11 and the actuating coils of 2 having a larger number of turns and consequently a greater inductance than those of 11, a description of one will suffice for both.

15 The electro-magnetic sound reproducer 2 comprises an enclosing cylindrical casing 18 open at its lower end and closed at its upper end by an integral closure member 19 terminating in a nipple 20 arranged to be frictionally engaged on its outside cylindrical surface by the lower securing portion 7 of horn 1 as shown. The horn 10 is similarly secured to 20 the sound reproducer 11.

25 A peripheral shoulder 21 is integral with the enclosing casing 18 and is contained therein. The low frequency diaphragm 22, constructed of appropriate diaphragm material, is spaced away from the closure member 19, resting against the outer surface of the shoulder 21 and is held in engagement therewith by means of a clamping ring 23 and screws 24 30 passing through registering holes in the periphery of the diaphragm and ring, the said screws being threaded in the body of shoulder 21.

35 The lower end of the casing 18 is internally threaded for the reception of a closure member 25 made of some suitable non-magnetic material and having an integral upwardly extending flange 26 externally threaded for engagement with the internally threaded 40 lower end of the enclosing casing 18.

45 The diaphragm actuating mechanism (of which Fig. 7 is a plan view) comprises a substantially U-shaped permanent magnet 27 suitably secured to the inner surface of the closure member 25. The free ends 28 and 29 of the permanent magnet are joined together by magnetic bridging members 30 and screws 31 as shown.

50 The magnetic bridging members 30, which are composed of a plurality of similar laminations united together, have two integral pole pieces 32, 32 extending toward the diaphragm 22. Magnetizing coils 33, 33 are mounted around said pole pieces and held in 55 place thereon by means of suitable insulated washers 34, 34. The operation of the diaphragm actuating mechanism, being well known in the art, requires no description here. The leads from the coils 33, 33 and 33', 33' 60 may be connected to insulated terminals 35, 35 and 35', 35' respectively mounted in the closure members 25 and 25' respectively as shown.

65 Independent control of the volume of sound emanating from the units may be ef-

fected by independently screwing the closure members 25 and 25' clockwise or counter-clockwise to thereby vary the spacing between the poles 32 and 32' and the diaphragms 22 and 22' respectively. This results in tonal quality control.

70 The coils of the electro-magnetic sound reproducers 2 and 11 are connected in series across the output terminals of the "source of received signals" as shown in Fig. 2. A condenser 36 is connected across the coils of the 75 reproducer 2 for a purpose to be hereinafter described.

75 The horn 1 and the diaphragm 22 of the sound reproducer 2 are arranged to be substantially resonant to the lower band of audible frequencies which are to be reproduced and amplified. The horn 10 and the diaphragm 22' of the sound reproducer 11 are arranged to be substantially resonant to the upper band of audible frequencies which are to be reproduced and amplified.

80 The coils of sound reproducers 2 and 11 and the condenser 36 are so arranged as to result in a substantially uniform impedance substantially equal to the impedance of the "source of received signals" over the entire range of audible frequencies to be reproduced and amplified. Substantially maximum uniform reproduction and amplification of the 85 frequencies to be reproduced and amplified over the entire range of audible frequencies with a minimum amount of power thereby results, or conversely, a maximum and substantially uniform volume of sound results 90 over the entire range of audible frequencies with a given amount of available power.

95 The condenser 36 together with the comparatively large inductance of the coils 33, 33 prevents the higher band of frequencies from 100 influencing the operation of the sound reproducer 2. The coils 33', 33', possessing comparatively small inductance, are readily influenced by the upper band of frequencies while the comparatively small diaphragm 22' 105 of the sound reproducer 11 is substantially non-responsive to the lower band of frequencies. The substantial elimination of the effects of interfering frequencies is therefore 110 effected.

115 We claim:

1. In combination, a plurality of intersecting sound amplifying horns each substantially resonant to a different portion of the audible range of frequencies, and an electro-acoustic device attached to each of said horns.

120 2. In combination, a pair of intersecting sound amplifying horns one of which is substantially resonant to the upper portion of the audible spectrum, the other of which is substantially resonant to the lower portion of the audible spectrum, and a pair of electro-acoustic devices attached to, and having similar frequency characteristics to, the horns.

125 3. A pair of intersecting sound amplifying

- horns, rigidly attached together at their line of intersection and at points along the peripheries of their outlets, each of said horns being substantially resonant to a different portion of the audible range of frequencies, and an electro-acoustic device attached to each of the horns, each device having frequency characteristics similar to the horn to which it is attached. 5
4. In an apparatus for the transformation of electrical undulations into sound vibrations, the combination of a plurality of electro-acoustic devices each substantially resonant to a predetermined portion of the audible frequency spectrum, each having independent means for varying the amplitude of vibration of a diaphragm in each of said electro-acoustic devices, said devices having intersecting sound amplifying horns rigidly united together at their line of intersection and partly along the peripheries of their outlets. 10
5. In an apparatus for the transformation of electrical undulations into sound vibrations, a pair of electro-acoustic devices one of which is substantially resonant to the lower range of the audible spectrum and the other of which is substantially resonant to the upper range of the audible spectrum, each of 15 said devices having independent means for varying the amplitude of vibration of a diaphragm in each of them, said devices having intersecting sound amplifying horns rigidly united together at their line of intersection and, in substantially one plane, partly along the peripheries of their outlets. 20
6. In combination, a pair of horns, one of which intersects and passes through at least one part of the other horn, each of said horns being resonant to a different portion of the audio frequency spectrum, and a separate source of sound energy for each horn. 25
7. In combination, a pair of intersecting horns, one of said horns adapted for amplifying frequencies of the lower portion of the audio frequency spectrum, the other horn being relatively short with reference to said first described horn, said other horn being adapted for amplifying the frequencies of 30 the upper portion of the audio frequency spectrum, and a separate source of sound energy for each horn. 35
8. A pair of intersecting sound amplifying horns attached together at their intersection and at their outlets. 40
9. A pair of sound amplifying horns of different size and shape intersecting intermediate their inlets and outlets, the outlets of the horns lying in substantially the same 45 plane and united together at a plurality of points in said plane, the intermediate portions of the horns being rigidly fastened together at their intersection. 50
10. In combination, a plurality of intersecting sound amplifying horns, each sub- 55
- stantially resonant to a different portion of the audible range of frequencies, an electro-acoustic device attached to each of said horns, and said horns being attached together at their outlets. 60
11. In combination, a plurality of intersecting sound amplifying horns, each substantially resonant to a different portion of the audible range of frequencies, an electro-acoustic device attached to each of said horns, and said horns being attached together at their intersections. 65
